UNITED STATES PATENT OFFICE

EDWARD J. GROSS, OF NEW ROCHELLE, NEW YORK

DESIGN FOR A FINGER RING OR ARTICLE OF SIMILAR NATURE

Application filed November 6, 1930. Serial No. 37,575. Term of patent 7 years.

To all whom it may concern:

Be it known that I, EDWARD J. GROSS, a citizen of the United States, residing at New Rochelle, in the county of Westchester and State of New York, have invented a new, original, and ornamental Design for a Finger Ring or Article of Similar Nature, of which the following is a specification, reference being had to the accompanying drawing, forming a part thereof.

Fig. 2 is an elevational view thereof.

Fig. 3 is a perspective view thereof.

The appearance of the bottom side of the ring is uniform and similar to that shown at the lower portion of Fig. 1.

I claim:

The ornamental design for a finger ring or article of similar nature as shown and described.

In testimony whereof I affix my signature.

EDWARD J. GROSS.
